DESIGN FOR A DRESS

Tora Coleman, New York, N. Y.

Application July 2, 1937, Serial No. 70,221

Term of patent 3½ years

To all whom it may concern:

Be it known that I, Tora Coleman, a citizen of Latvia, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

My design is characterized by the panel effect on the rear portion of the dress, the top of the panel lapping over at the shoulders and forming a collar on the front of the dress as shown. The flaps on the skirt portion of the dress are continued from the rear of the dress and give the appearance of pockets.

I claim:

The ornamental design for a dress substantially as shown and described.

TORA COLEMAN.
